(57) CLAIM

The ornamental design for a plant figurine, as shown.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright work) rights whatsoever.

FIG. 1 is a front perspective view from above of a plant figurine showing my new design;

FIG. 2 is a front orthogonal view thereof;

FIG. 3 is a rear orthogonal view thereof;

FIG. 4 is a left side orthogonal view thereof;

FIG. 5 is a right side orthogonal view thereof;

FIG. 6 is a top orthogonal view thereof; and,

FIG. 7 is a bottom orthogonal view thereof.

Broken lines in the disclosure are understood to be for illustrative purposes only and do not form part of the claimed design.
